[57] **CLAIM**

The ornamental design for a combined case and cover
for a quick mount combination lock, as shown and de-
scribed.

DESCRIPTION

FIG. 1 is a front elevational view of a combined case
and cover for a quick mount combination lock, em-
bodying my new design;

FIG. 2 is a top plan view thereof, the bottom view being
the mirror image thereof;

FIG. 3 is a rear elevational view thereof;

FIG. 4 is an end elevational view thereof, viewed from
the right of FIG. 3;

FIG. 5 is an end elevational view thereof, viewed from
the left of FIG. 3.
